[57] CLAIM

The ornamental design for an oral medication cup, as shown and described.

DESCRIPTION

FIG. 1 is a front perspective view of an oral medication cup showing my new design;

FIG. 2 is a rear perspective view thereof;

FIG. 3 is a top plan view thereof;

FIG. 4 is a bottom plan view thereof;

FIG. 5 is a side elevational view thereof;

FIG. 6 is a side elevational view of the side opposite that shown in FIG. 5;

FIG. 7 is a front elevational view thereof;

FIG. 8 is a rear elevational view thereof;

FIG. 9 is a sectional view taken along line 9—9 of FIG. 5;

FIG. 10 is a side elevational view thereof shown in open position, the opposite side elevational view being identical thereto; and,

FIG. 11 is a top plan view.
